UNITED STATES PATENT OFFICE.

FRANCIS N. POIGNAND, OF RUTHERFORD, NEW JERSEY, ASSIGNOR TO LOCOMOTIVE SUPERHEATER COMPANY, OF NEW YORK, N. Y., A CORPORATION OF DELAWARE.

SUPERHEATER.

1,260,443.

Specification of Letters Patent. Patented Mar. 26, 1918.

Application filed December 22, 1917. Serial No. 208,471.

To all whom it may concern:

Be it known that I, FRANCIS NESBITT POIGNAND, a subject of the King of England, residing at Rutherford, in the county of Bergen and State of New Jersey, have invented certain new and useful Improvements in Superheaters, of which the following is a specification.

My invention relates to superheaters, and more particularly to superheaters of the type wherein the tubular units making up the superheater are located in the flues or tubes of a boiler. The ends of the units of this type of superheater are secured to a header or headers, and various ways of securing them have been proposed. The present invention has for its purpose the provision of improved means of establishing connection between the units and the header. This statement of purpose is to be taken in its broadest sense, as covering a modification or re-arrangement of the unit which may become necessary.

The invention is fully described in the following specification which is to be read in connection with the accompanying drawings forming part hereof. In these drawings, Figure 1 is a sectional view of the front part of a locomotive boiler, on line 1—1 of Fig. 2, looking in the direction indicated by the arrows; Fig. 2 is a view on line 2—2 of Fig. 1, in the direction of the arrows; Fig. 3 is a section, on an enlarged scale, on line 3—3 of Fig. 2; Fig. 4 is a section of Fig. 3 on line 4—4. Fig. 5 is a fragmentary sectional view on line 5—5 of Fig. 4, the subheader being raised off its seat; Figs. 6 to 9 are sectional views, similar to Figs. 3 and 4, of modifications; Figs. 10 to 13 are sectional views similar to Figs. 1 and 2 of modifications, the views being taken respectively on lines 10—10, 11—11, 12—12, and 13—13; Fig. 14 is a front view, part of it in section on line 14—14 of Fig. 15, and parts being omitted, of a marine superheater according to my invention; Fig. 15 is a top view of same, the flues being shown in central longitudinal section; Figs. 16 and 17 show views, similar to Figs. 14 and 15 of a modification; Fig. 18 is a section on line 18—18 of Fig. 19; Fig. 19 is an enlarged top view of two of the subheaders of Fig.

16; Figs. 20 and 21 are sectional views on lines 20—20 and 21—21 respectively of Fig. 16.

Referring first to the form of my device shown in Figs. 1 and 2, reference numeral 1 designates the boiler, 2 the flue sheet, 3 the flues, and 4 the superheater units. These units, it will be noted, have in the case shown two loops each, looping into separate flues, each flue accommodating two loops, but of different units. The ends of these units are welded or otherwise secured into the openings 5 of the subheader 6 (see Figs. 3 and 4). The openings 5 into which the ends of any one unit are secured lie on opposite sides of the partition 7 in subheader 6. Each subheader 6 is secured to the header 8 by means of its bolt 9, which passes through the partition 7 and is screwed into wall 10 of header 8. This wall 10 divides header 8 into two compartments 11 and 12, into one of which, 11, steam is delivered from the boiler, and from the other, 12, of which it is carried to the engine. The subheader 6 is kept in such position, by means of the lugs 13 on it and 14 on the header, relative to the header 8 that the two partitions 7 and 10 are always in alinement. The seat between the subheader 6 and the header 8 is spherical, so that a slight movement between the two is possible without a leak resulting.

As will be clear from Fig. 2, the header 8 is divided into two branches. Only one of these is shown, the other being symmetrical with it. There are shown four subheaders 6 attached to the branch shown and four units to each subheader, though evidently either or both of these arrangements may be varied.

Figs. 6 and 7 show a variation of the means for securing the subheaders. Instead of the single bolt 9, two bolts 9^a and 9^b, on opposite sides of the subheaders are employed. They pass through ears 15 and are screwed into the header wall. Lugs 13 and 14 are then superfluous.

A still different means of attachment is shown in Figs. 8 and 9. Here a clamp 16 lies across the outer end of the subheader, and bolts 9^c and 9^d pass through it near its opposite ends and are screwed into the

header wall. Pins 17, integral with the sub-header, and engaging with corresponding openings in clamp 16, keep the subheader from rotating.

- 5 The operation of the device calls for no lengthy statement, but will be evident to any one familiar with this art. Saturated steam from the boiler is delivered into chamber 11 of header 8. From this chamber it flows to 10 the chambers of the several subheaders in communication with chamber 11. It leaves these by one set of the openings 5 and flows through the superheater units 4, where it is superheated by the hot gases flowing 15 through the flues 3, returning to the other chambers of the subheaders, *i. e.* those communicating with the chamber 12 of header 8. From 12 the steam is carried to the point where it is to be used.
- 20 In the form of the device illustrated in Figs. 10 and 11, the connections by which steam is carried from chamber 12 of the header 8 are made at the top, instead of at the bottom as in the first form, and instead 25 of two branches, header 8 has four, two only of which are shown. The number of units connected with each subheader is half as great as in the first form; otherwise this modification calls for no further description.

30 Figs. 12 and 13 show a form for use in small boilers, where only a small number of flues are to be supplied with units. There is a single branch to the header in this case, 35 and two subheaders on each side of it, each with four units supplying four flues. The details of the subheaders, and the action of the apparatus will be evident from what was said above.

40 The forms of the device so far described are intended particularly for use with boilers of the locomotive type; the forms of Figs. 14 to 17 are for use in return tubular boilers such as are used particularly in marine work. In these cases the flues used are customarily smaller and only one loop of a unit is put into each flue.

The header of Figs. 14 and 15 has two 50 chambers separated by the wall 18, one of the chambers for saturated steam to be delivered to the units, the other to receive the superheated steam from the units. The two chambers are seen to have intermeshing portions, 19 and 20, and it is with two such adjacent portions that each subheader communicates. The method shown in this figure for attaching the subheaders is a little different from those described before. The clamps 21 bear on the tops of two adjacent subheaders and are held by central bolts 22. The subheaders have the central partition as before, which here seats on the wall between spaces 19 and 20.

In the modification of Figs. 16 to 21,

saturated steam is admitted at the nozzle 65 23 and superheated steam leaves at 24. The spaces 25 and 26 communicate freely with space 27, while the spaces 28 and 29 are in free communication with space 30; but 25 and 26 do not directly open into 30, nor do 70 28 and 29 open directly into 27. The sub-headers each communicate with one space 25 or 26 and an adjacent space 28 or 29, their partition wall registering with the corresponding partition wall in the header. The 75 connection of the units corresponds with that in the previously described cases, and the operation of this form of the apparatus will be obvious.

It will be clear that the above described 80 forms of my apparatus merely illustrate my invention, and that there are numerous variations and modifications possible. These, in as far as they are within the spirit of the subjoined claims, I regard as part of my invention.

What I claim is:—

1. In apparatus of the class described, a header having a partition wall and an opening divided by said partition wall, a sub-header of cylindrical shape having a diametrical partition wall, said subheader being closed at one end and open at the other, a bolt passing longitudinally through the partition wall of the subheader and screwed 95 into the partition wall of the header and holding the subheader to the header, the two partition walls registering, the engaging surfaces of the header and subheader being spherical.

2. In apparatus of the class described, the combination of a header having a partition wall and a circular opening diametrically divided by said wall; a cylindrical sub-header having a diametrical partition wall, 105 means to hold said subheader to said header in such position that the two partition walls register, the contacting points of the header and subheader and their partition walls lying in a spherical surface, allowing slight 110 angular movements of the subheader relative to the header.

3. In apparatus of the class described, the combination of a header having a partition wall and a circular opening diametrically divided by said wall, a cylindrical sub-header having a diametrical partition wall and having one end closed and the other open, a single bolt holding the header to the subheader in such position that the partition 120 walls register, the contacting points of the header and subheader and their partition walls lying in a spherical surface, a superheater unit secured to the subheader its ends opening respectively into the two chambers of the subheader.

4. In apparatus of the class described, the combination of a header, a partition

wall in said header, the header having a circular opening bisected by said partition wall, a cylindrical subheader with a partition bisecting it diametrically, the subheader being open at one end and closed at the other, means to hold the header and subheader in engagement in such manner that the partition walls register and the interior spaces on the two sides of the subheader partition com-

municate respectively with the two spaces in 10 the header, the contacting points of the header, subheader and partitions lying in a spherical surface, and a plurality of superheater units, one end of each being welded into and opening into one of the spaces in 15 the subheader, the other end being welded into and opening into the other.

FRANCIS N. POIGNAND.
